UNITED STATES PATENT OFFICE.

EDWARD G. ROWLEY, OF BELLEVILLE, NEW JERSEY, ASSIGNOR TO UNDERWOOD
ELLIOTT FISHER COMPANY, OF NEW YORK, N. Y., A CORPORATION OF DELAWARE.

TYPEWRITING MACHINE.

Application filed May 12, 1926. Serial No. 108,495.

This invention relates to sound-deadening casings for typewriting machines, and is especially intended for use in connection with machines of the portable class.

5 The machine may be mounted upon a base-board, and provided with a sheet-metal casing including a displaceable top having a glass panel. The keyboard of the machine protrudes to the exterior of the casing and 10 is operated in the regular way. The carriage is controlled from the outside of the casing by means of a handle pivotally mounted in the casing, and effective by means of a gear-sector and pinion to revolve 15 a drum. A cord is wound around this drum and connected to the line-space lever of the machine to return the carriage and line-space the platen.

Another feature of the invention relates 20 to novel means for releasing the carriage without necessitating the lifting of the cover, and this means includes a bar extending lengthwise within the casing and engageable with the carriage-release lever. 25 The bar is pivotally mounted in the end walls of the casing, and is normally held free from the carriage-release lever by means of a spring, the bar being swingable into engagement with the lever upon the depression of a button provided on the outside 30 of the casing.

Another feature of this invention relates 35 to novel means for resiliently securing the machine to the base-board in a manner to further soften the noise arising from the operation thereof. To this end, there is provided a pad of sound-deadening material upon which the feet of the machine rest. At the rear thereof, the machine is secured to 40 the board by means of a clip permanently secured to the board. Said clip has a hook designed to engage in a hole in the rear wall of the machine-frame. The front part of the machine is secured to the board by means of 45 screws which are passed through brackets fast to the frame and screwed into threaded plugs driven into the board from the bottom thereof.

Other features and advantages will hereinafter appear.

In the accompanying drawings,

Figure 1 is a plan view of the sound-deadening casing with the cover removed.

Figure 2 is a front view of the casing, and

is partly shown in cross-section to show 55 some of the operating mechanism.

Figure 3 is a perspective view, showing a special scale for indicating the position of the carriage.

Figure 4 is a cross-sectional view, showing 60 the drum and the operating handle.

Figure 5 is a cross-sectional view, showing 65 the means for securing the machine to the base-board of the casing.

Figure 6 is a cross-sectional view, showing 70 65 the means for operating the carriage-release lever.

The Underwood portable machine is provided with a frame 10 having a front extension 11, which encloses a series of 75 depressible keys 12 and a traveling carriage 13, which is normally returnable by means of a line-space lever 14. The frame 10 is secured to a base-board 15 by means of a clip 17 80 designed to engage in a hole 18 in the rear wall 19 of the frame, said base-board being provided with a felt covering 16. The clip is permanently fast to the base-board by means of screws 20, and the machine is cushioned with a felt pad 21, mounted between the base-board and feet 22 fast to the frame, as shown in Figure 5. The front part of the machine is provided with angular plates 23, fast to the frame by means of screws 24. The angular plates 23 are 85 perforated to receive screws 25, which are threaded into metal plugs 26 driven into the board. To further cushion the machine, there may be provided rebound rubber washers or sleeves 27 under the heads of the 90 screws 25.

In order to deaden the sound arising from the operation of the machine, there is provided a casing having a rear wall 28 and side walls 29. The rear and side walls may 95 be made of a continuous piece of sheet-metal, which may be further extended at the front thereof to provide a front wall 30. The front wall 30 has an opening 31, through which the keyboard-extension 11 protrudes 100 to the exterior of the casing, thereby rendering the keyboard operable. The walls of the casing are fast to the base-board 15 by means of screws 32.

According to certain features of this invention, there is provided a front plate 33, 105 which is shaped to conform with the front wall of the machine, as shown in Figure 2.

Said plate is lined with sound-deadening material 34, and has extensions or plates 35 fast thereto by means of rivets 36, the plates being provided with slots 37 designed to engage studs 38 fast to the front wall of the casing. The plate 33 is secured to the front wall by means of winged nuts 39.

The carriage-return lever 14 is provided with an arm 40, secured thereto by means of a screw 41. Said arm carries at the end thereof a cord 42 wound around a drum 43 fast to a shaft 44. Said shaft is journaled in a supporting bracket or base 45, and carries at the end thereof a beveled gear 46 designed to engage a gear-sector 47 pivotally mounted upon a shaft 48. The sector is normally held in the position shown in Figure 4 by means of a comparatively light spring 49, which is effective to take up the slack of the cord and is wound around the shaft 48. The tension of the spring may be adjusted by rotating the shaft 48, which is subsequently locked in position by means of a screw 50.

The carriage may be returned, after each line of typing, by means of a handle 51 mounted at the end of a lever 52, which may form an integral part of the sector 47. The lever 52 passes through a slot 53 in the front wall 30. It will be noted that, as the carriage is letter-spaced, the cord 42 will rotate the drum 43, and thereby lift the handle 51, which will reach its uppermost position when the carriage reaches its extreme left-hand position. Then, in order to return the carriage, it is only necessary to depress the handle 51. The drum 43 is provided with a guard 54, to retain the cord 42 in a groove 55. Said guard is held in place by means of a screw 56, which prevents the guard from rotating. The screw may be locked by means of a nut 57. It will be seen that the carriage-returning devices described are all carried on the base 45, and form therewith a unit which is readily attachable to the base-board 15.

A carriage-release lever 58 is pivotally mounted on a platen-shaft 59, and engages with an intermediate lever 60, which carries a rack 61 operatively connected to a line-spacing mechanism 62. Said lever 58 is depressible, to thus free the carriage and permit the movement thereof, by means of a cross-bar 63, which is journaled in holes 64 in the end walls of the casing. The cross-bar is operatively connected, by means of an arm 65, to a finger-piece 66, carried by a rod 67, slidably mounted in the front wall of the casing. The rod 67 is mounted by means of a pin 68, on the arm 65, and is held in its ineffective position by means of a spring 69, actuating between the arm 65 and a supporting bracket 70, fast to the base-board by means of one of the screws 32, as shown in Figure 6.

In order to facilitate the positioning of the carriage without necessitating the displacement of the cover, there is provided a special scale 71, mounted upon the front wall of the casing by means of a frame 72, both the frame and the scale being secured to the casing by means of screws 73. The face of the scale is graduated to correspond with the graduations on the regular scale on the carriage, which determine the position thereof, and is curvated radially with the axis of the shaft 48. Since the purpose of this scale 71 is to indicate the position of the carriage relative to the printing point, there is provided an indicator or pointer 74, which may be secured to the lever 52 by means of rivets 75.

The noise ensuing from the operation of the machine is confined within the casing by providing a sound-deadening lining 76 and a cover 77. The latter is pivotally mounted upon a hinge 78, and is provided with a glass panel 79, which is secured to the cover by means of clips 80.

Since the unused portion of the work-sheet is confined within the casing, the trailing edge thereof is liable to drag along the felt lining and otherwise engage with some of the operating mechanism within the casing. To overcome this, there is provided a sheet-metal plate 81, which is curled at the bottom thereof to form a channel, as shown in Figure 4. The plate may be secured to the rear wall of the casing by means of screws 82.

Variations may be resorted to within the scope of the invention, and portions of the improvements may be used without others.

Having thus described my invention, I claim:

1. A carriage-return mechanism for a typewriting machine having a traveling carriage and a carriage-return lever therefor, said mechanism including, in combination, a rotatably-mounted drum, a cord wound therearound, the cord having one end fast to the drum and the other end fast to the carriage-return lever, a bevel gear operatively connected to said drum in a manner to rotate therewith, a geared sector meshing with said gear, a pivot-shaft for said sector, and a handle for swinging said sector to thus rotate the drum and return the carriage.

2. A carriage-return mechanism for a typewriting machine having a traveling carriage and a carriage-return lever therefor, said mechanism including, in combination, a rotatably-mounted drum, a cord wound therearound, the cord having one end fast to the drum and the other end fast to the carriage-return lever, said drum having a peripheral groove for receiving the cord, means for holding the cord in the groove, said means including a guard for completely encasing the drum except for a cut-away por-

tion that permits the passing of the cord from the exterior of the guard to the drum, and means for rotating said drum, said last-mentioned means including a shaft for the drum, a bevel gear carried by said shaft, and a manually-operable geared sector for engaging said gear.

3. A carriage-return mechanism for a typewriting machine having a traveling carriage and a carriage-return lever therefor, said mechanism including, in combination, a rotatably-mounted drum, a cord wound therearound, the cord having one end fast to the drum and the other end fast to the carriage-return lever, said drum having a peripheral groove for receiving the cord, means for holding the cord in the groove, said means including a guard for completely encasing the drum except for a cut-away portion that permits the passing of the cord from the exterior of the guard to the drum, means for rotating said drum, said last-mentioned means including a shaft for the drum, a bevel gear carried by said shaft, and a manually-operable geared sector for engaging said gear, and means associated with said geared sector for indicating the position of the carriage relatively to the printing point of the machine.

4. A carriage-return mechanism for controlling a typewriting machine in a sound-deadening casing from the exterior thereof, the machine having a traveling carriage and a carriage-return finger-piece therefor, said mechanism including, in combination, a rotatably-mounted drum having a cord wound therearound, said cord having one of its ends fast to the drum and the other end fast to said finger-piece in a manner to draw the carriage toward the drum when the drum is rotated, means for manually rotating said drum, said means including a bevel gear, a geared sector, and a handle fast to said sector, said handle protruding to the exterior of the casing through a slot in the wall thereof, and means associated with said handle for indicating the position of the carriage relatively to the printing point of the machine.

5. A carriage-return mechanism for controlling a typewriting machine in a sound-deadening casing from the exterior thereof, the machine having a traveling carriage and a carriage-return finger-piece therefor, said mechanism including, in combination, a rotatably-mounted drum having a cord wound therearound, said cord having one of its ends fast to the drum and the other end fast to said finger-piece in a manner to draw the carriage toward the drum when the drum is rotated, means for manually rotating said drum, said means including a bevel gear, a geared sector, and a handle fast to said sector, said handle protruding to the exterior of the casing through a slot in the wall

thereof, and means associated with said handle for indicating the position of the carriage relatively to the printing point of the machine, said last-mentioned means including a fixed graduated scale and a pointer carried by said handle, the graduations on the scale corresponding to the letter-space movement of the carriage.

6. Means for resiliently securing a typewriting machine to the baseboard of a sound-deadening casing, said means including, in combination, a felt pad under the feet of the machine, a clip at the rear of the machine, said clip engaging in a hole in the rear wall of the machine, brackets fast to the frame of the machine at the front thereof, screws for securing said brackets to the base-board, and threaded plugs carried by said base-board for receiving said screws.

7. A sound-deadening casing for a typewriting machine having a frame, a keyboard and a traveling carriage, the casing including a body-part and a cover therefor, the body-part including a base-board, rear, side and front walls, the latter having a keyboard-opening, and means for returning the carriage after each line of typing, said means including a handle adjacent the keyboard, said handle being pivotally mounted on a shaft in the casing and protruding to the exterior of the casing through a slot in the front wall thereof, a drum in the casing, a cord wound therearound, said cord having one end fast to the drum and the other end fast to the carriage, and means for operatively connecting said drum with said handle in a manner to revolve the drum upon operation of the handle.

8. A sound-deadening casing for a typewriting machine having a frame, a keyboard and a traveling carriage, the casing including a body-part and a cover therefor, the body-part including a base-board, rear, side and front walls, the latter having a keyboard-opening, and means for returning the carriage after each line of typing, said means including a handle adjacent the keyboard, said handle being pivotally mounted on a shaft in the casing and protruding to the exterior of the casing through a slot in the front wall thereof, a drum in the casing, a cord wound therearound, said cord having one end fast to the drum and the other end fast to the carriage, and means for operatively connecting said drum with said handle in a manner to revolve the drum upon operation of the handle, said last-mentioned means including a geared sector forming an integral part of said handle and a bevel gear mounted with the drum in a manner to revolve therewith, said bevel gear engaging with the geared sector in a manner to revolve the drum upon operation of the handle.

9. A sound-deadening casing for a type-

writing machine having a frame, a keyboard and a traveling carriage, the casing including a body-part and a cover therefor, the body-part including a base-board, rear, side and front walls, the latter having a keyboard-opening, and means for returning the carriage after each line of typing, said means including a handle adjacent the keyboard, said handle being pivotally mounted on a shaft in the casing and protruding to the exterior of the casing through a slot in the front wall thereof, a drum in the casing, a cord wound therearound, said cord having one end fast to the drum and the other end fast to the carriage, means for operatively connecting said drum with said handle in a manner to revolve the drum upon operation of the handle, said last mentioned means including a geared sector forming an integral part of said handle and a bevel gear mounted with the drum in a manner to revolve therewith, said bevel gear engaging with the geared sector in a manner to revolve the drum upon operation of the handle, and a graduated scale mounted upon the front wall of the casing for indicating the position of the carriage relative to the printing point of the machine.

10. A sound-deadening casing for a typewriting machine having a frame, a keyboard and a traveling carriage, the casing including a body-part and a cover therefor, the body-part including a base-board, rear, side and front walls, the latter having a keyboard-opening, and means for returning the carriage after each line of typing, said means including a handle adjacent the keyboard, said handle being pivotally mounted on a shaft in the casing and protruding to the exterior of the casing through a slot in the front wall thereof, a drum in the casing, a cord wound therearound, said cord having one end fast to the drum and the other end fast to the carriage, means for operatively connecting said drum with said handle in a manner to revolve the drum upon operation of the handle, said last-mentioned means including a geared sector forming an integral part of said handle and a bevel gear mounted with the drum in a manner to revolve therewith, said bevel gear engaging with the geared sector in a manner to revolve the drum upon operation of the handle, a graduated sector fast to the front wall of the casing, said graduated sector having a slot through which the handle passes to the outside thereof, and a pointer carried by said handle, said pointer co-operating with the graduations on the graduated sector to indicate the position of the carriage in relation to the printing point of the machine.

11. The combination with a typewriting machine including resilient feet and a base-board, of an intermediate base of sound-deadening material between said resilient

feet and the base-board, and means for securing the machine to said base-board in a manner to hold said machine in working position on the intermediate base, while preserving the resiliency of said feet and the sound-deadening qualities of said base, said means including a clip at the rear of the machine, said clip engaging in a hole in the rear wall of the machine, brackets fast to the frame of the machine at the front thereof, and screws for securing said brackets to the base-board.

12. The combination with a typewriting machine including resilient feet and a base-board, of an intermediate base of sound-deadening material between said resilient feet and the base-board, and means for securing the machine to said base-board in a manner to hold said machine in working position on the intermediate base, while preserving the resiliency of said feet and the sound-deadening qualities of said base, said means including a clip at the rear of the machine, said clip engaging in a hole in the rear wall of the machine, brackets carried by the frame of the machine, headed screws passing through openings in the brackets and the intermediate base, and then into holding relation with the base-board, and resilient sound-deadening sleeves carried by said screws between the heads thereof and the brackets.

13. The combination with a sound-deadening casing for enclosing a typewriting machine including a carriage and a release-lever therefor, of means operable from the outside of the casing for actuating said release-lever, said means including a displaceable bail carried by the casing and operatively associated with the release-lever, an arm fixed to the bail, a spring having one end connected to the free end of said arm and the other end held stationary, said spring being effective to maintain said bail in non-releasing position, and an outside button connected to said arm in a manner to operate said bail and thereby actuate the release-lever against the action of said spring.

14. The combination with a typewriting machine including a platen-carriage, line-spacing and carriage-returning mechanism and a sound-deadening casing for the machine, including a base upon which the machine is mounted, of means for operating said mechanism from the outside of the casing, said means being in the form of a self-contained unit positioned within the casing and secured to the base adjacent one end of the casing and including an operating handle extending through an opening in the front wall of said casing to the exterior thereof, and operating connections between said handle and said line-spacing and carriage-returning mechanism.

15. The combination with a typewriting machine including a platen-carriage, line-

- spacing and carriage-returning mechanism and a sound-deadening casing for the machine, of means for operating said mechanism from the outside of the casing, said 5 means being in the form of a self-contained unit positioned within the casing and including an operating handle extending through an opening in said casing to the exterior thereof, operating connections between said handle and said line-spacing and carriage-returning mechanism, a graduated letter-space scale at the outside of the casing, and a pointer operated by the handle for indicating on said graduated scale each letter-space position of the enclosed platen-carriage.
16. The combination with a typewriting machine including a platen-carriage, line-spacing and carriage-returning mechanism 20 and a sound-deadening casing for the machine, of means for operating said mechanism from the outside of the casing, said means being in the form of a self-contained unit positioned within the casing and including a base, a winding drum, a cord having one end attached to the drum and the other end connected to the line-space lever, a handle extending through an opening in the front of the casing to the exterior thereof, operating connections between the handle and the drum, and a pointer carried by the handle, said casing carrying a graduated letter-space scale on the outside thereof and co-operating with said pointer to indicate each letter-space position of the enclosed platen-carriage.
17. The combination with a typewriting machine including a platen-carriage, line-spacing and carriage-returning mechanism 25 and a sound-deadening casing for the machine, of means for operating said mechanism from the outside of the casing, said means being in the form of a self-contained unit positioned within the casing and including a base, a winding drum including a shaft, a cord having one end attached to the drum and its other end connected to the line-space lever, journals for the shaft, a push-down handle extending through an opening 30 in the front wall of the casing to the exterior thereof, said base also including a mounting for said handle, and a pointer carried by the handle, said casing carrying a graduated letter-space scale on the outside thereof and co-operating with said pointer to indicate on said graduated scale each letter-space position of the enclosed platen-carriage.
18. The combination with a typewriting machine including a platen-carriage, line-spacing and carriage-returning mechanism, and a sound-deadening casing for the machine, of means for operating said mechanism from the outside of the casing, said 35 means being in the form of a self-contained unit positioned within the casing and including a base, a winding drum including a shaft, a cord having one end attached to the drum and its other end connected to the line-space lever, a guard for retaining and guiding the cord on the drum, journals for the shaft, a bevel gear fixed to said shaft, a push-down handle extending through an opening in the front wall of the casing to the exterior thereof, a sector-gear operated by said handle and meshing with said bevel gear, a standard carried by said base and upon which said handle is operatively mounted, a spring co-operating with said handle to maintain the same in position and to keep said cord in taut condition between the drum and the line-space lever, and an indicator operated by the handle, said casing including a letter-space scale secured to the outside front wall thereof, said scale having a slot in which said handle is arranged to move and also having letter-space graduation-marks at both sides of the slot, said indicator being arranged to travel in the scale-slot to point out on said graduation-marks each letter-space position of the enclosed platen-carriage.
19. The combination with a typewriting machine including a platen-carriage, line-spacing and carriage-returning mechanism 40 and a sound-deadening casing for the machine, of means for operating said mechanism from the outside of the casing, said means being in the form of a self-contained unit positioned within the casing and including a base, a winding drum including a shaft, a cord having one end attached to the drum and its other end connected to the line-space lever, a guard for retaining and guiding the cord on the drum, journals for the shaft, a bevel gear fixed to said shaft, a push-down handle extending through an opening in the front wall of the casing to the exterior thereof, a sector-gear operated by said handle and meshing with said bevel gear, a standard carried by said base and upon which said handle is operatively mounted, a spring co-operating with said handle to maintain the same in position and to keep said cord in taut condition between the drum and the line-space lever, and an indicator operated by the handle, said casing including a letter-space scale secured to the outside front wall thereof, said scale having a slot in which said handle is arranged to move and also having letter-space graduation-marks at both sides of the slot, said indicator being arranged to travel in the scale-slot to point out on said graduation-marks each letter-space position of the enclosed platen-carriage.
20. The combination with a portable typewriting machine and a baseboard, of means 45

for securing the machine to said baseboard, including a clip mounted on the baseboard at the rear of the machine, said clip engaging a hole in the rear wall of the machine, 5 brackets carried by the front portion of the frame of the machine, headed screws passing through openings in the brackets and into holding relation with the baseboard, and resilient sound-deadening material carried 10 by said screws between the heads thereof and the brackets.

21. The combination with a sound-deadening casing for enclosing a typewriting machine, including a carriage and a release-lever therefor, of operable means within the casing for actuating said release-lever, a spring effective to maintain said operable means in non-releasing position, and an operating member on the outside of the casing 15 connected with said operable means for actuating the release-lever against the action of said spring.

22. A carriage-return mechanism for a typewriting machine having a traveling carriage and a carriage-return lever therefor, 25 said mechanism including, in combination, a rotatable drum, a cord wound therearound, the cord having one end fast to the drum and the other end fast to the carriage-return lever, a gear operatively connected to said drum in a manner to rotate therewith, 30 a driving gear meshing with said gear, a handle for operating said driving gear and thus rotate the drum and return the carriage, and a spring operative upon said driving gear and handle for taking up any 35

play between the gears and the slack of the cord.

23. The combination with a sound-deadening casing for enclosing a typewriting machine, of a carriage-return mechanism for the typewriting machine having a traveling carriage and a carriage-return lever therefor, said mechanism including, in combination, 40 a rotatable drum, a cord wound therearound, the cord having one end fast to the drum and the other end fast to the carriage-return lever, a handle extending outside of the casing and having an operative connection for rotating said drum to return the carriage, and a spring operative upon 45 said handle for taking up any play between the handle and said drum and the slack of the cord.

24. The combination with a sound-deadening casing for enclosing a typewriting machine, of a carriage-return mechanism for the typewriting machine having a traveling carriage and a carriage-return lever therefor, said mechanism including, in combination, 50 a rotatable drum, a cord wound therearound, the cord having one end fast to the drum and the other end fast to the carriage-return lever, a handle extending outside of the casing and having an operative connection for rotating said drum to return the carriage, a spring operative upon 55 said handle for taking up any play between the handle and said drum and the slack of the cord, and means for adjusting 60 the tension of said spring.

EDWARD G. ROWLEY.
